CLAIM

We claim the ornamental design for a case for a computing device, as shown and described.

DESCRIPTION

FIG. 1 is an upper perspective view of the case for a computing device;

FIG. 2 is a lower perspective view of the case for a computing device shown in FIG. 1;

FIG. 3 is a front plan view of the case for a computing device shown in FIG. 1;

FIG. 4 is rear plan view of the case for a computing device shown in FIG. 1;

FIG. 5 is a left plan view of the case for a computing device shown in FIG. 1;

FIG. 6 is a right plan view of the case for a computing device shown in FIG. 1;

FIG. 7 is a top plan view of the case for a computing device shown in FIG. 1; and,

FIG. 8 is a bottom plan view of the case for a computing device shown in FIG. 1.

The subject matter shown in dashed lines, and any surfaces of the design not shown, including interior surfaces, form no part of the claimed design.
